Primary Examiner—James M. Gandy*Attorney, Agent, or Firm*—Thomas A. Lennox**[57]****CLAIM**

The ornamental design for a hood for an automobile, as shown and described.

DESCRIPTION

FIG. 1 is a top plan view of a hood for an automobile of the present invention;

FIG. 2 is a front elevational view thereof;

FIG. 3 is a rear elevational view thereof;

FIG. 4 is a left elevational view thereof;

FIG. 5 is a bottom plan view thereof;

FIG. 6 is a right side elevational view thereof;

FIG. 7 is a top plan view of a second embodiment of the invention;

FIG. 8 is a left elevational view thereof, the right elevational view being a mirror image thereof and the front and rear elevational views thereof are identical to FIGS. 2 and 3 respectively; and,

FIG. 9 is a bottom plan view thereof.
